UNITED STATES PATENT OFFICE.

PHILIP DIEHL AND ALFRED GRIEB, OF ELIZABETH, NEW JERSEY, ASSIGNEES TO THE SINGER MANUFACTURING COMPANY, OF NEW JERSEY.

DESIGN FOR A THREAD-CASE FOR SEWING-MACHINES.

SPECIFICATION forming part of Design No. 34,184, dated March 5, 1901.

Application filed February 8, 1901. Serial No. 46,585. Term of patent 14 years.

To all whom it may concern:

Be it known that we, PHILIP DIEHL and ALFRED GRIEB, citizens of the United States, residing at Elizabeth, in the county of Union and State of New Jersey, have invented and produced a certain new and original Design for Thread-Cases for Sewing-Machines, of which the following is a specification, reference being had therein to the accompanying drawings, forming part thereof.

The leading or material feature of our design comprises a thread-case of general segmental form having in its larger peripheral portion a groove the bottom wall of which is curved in the true arc of a circle and a portion of the peripheral part of which is curved in the arc of a smaller circle than that of which the bottom wall of said groove is an arc, the said thread-case having a circular cavity which is eccentrically disposed relative to the center of the circle of which the bottom wall of said groove is an arc.

In the drawings, Figures 1 and 2 are opposite side views of a thread-case embodying our design. Fig. 3 is a cross-section on line 3-3, Fig. 1; and Fig. 4 is an edge view of the thread-case.

Referring to the drawings, *a* denotes the segmental body of the thread-case, in the larger peripheral part of which is formed a groove *b*, having its bottom wall *c* (denoted by dotted lines in Figs. 1 and 2) curved in

the true arc of a circle, said groove being formed between two curved flanges *d* and *e* of different radial extents and the outer or 35 larger flange *d* having one end formed into a pointed portion or beak *f*. The thread-case body contains a circular cavity *g*, which is eccentric to the circle of which the bottom wall *c* of the groove *b* is an arc, the circular 40 wall *h* of said cavity being of greater extent than the thickness of the larger peripheral part of the thread-case, so as to extend outward beyond (or above and below) both sides thereof, as more clearly shown in Fig. 4, a 45 portion of the said circular wall *h* forming that part of the periphery of the thread-case which is curved in the arc of a smaller circle than the circle of which the bottom wall of the groove *b* is an arc. Between the flanges 50 *d* and *e* and the outwardly-extending circular wall *h* of the cavity *g* are outwardly curved or inclined bridge-pieces *i*.

We claim—

The design for a thread-case for sewing- 55 machines herein shown and described.

In testimony whereof we affix our signatures in the presence of two witnesses.

PHILIP DIEHL.
ALFRED GRIEB.
